E. J. Sigeris

ATTORNEY

UNITED STATES PATENT OFFICE.

GEORGE FENWICK WARREN, OF PORTSMOUTH, VIRGINIA.

BARREL.

1,246,510.

Specification of Letters Patent.

Patented Nov. 13, 1917.

Application filed November 28, 1916. Serial No. 133,963.

To all whom it may concern:

Be it known that I, GEORGE F. WARREN, a citizen of the United States, residing at Portsmouth, in the county of Norfolk and State of Virginia, have invented a new and useful Barrel, of which the following is a specification.

This invention relates to barrels, and especially to such as are used for truck purposes.

The object of the invention is to provide a barrel, which will comprise less material than those now on the market, and which will be much lighter, and at the same time a construction which will be stronger, more durable, and well ventilated.

The above object is attained by interweaving flexible strips or staves of wood, or the like, or similar thin flexible material in and out of solid rigid stiff hoops.

Referring to the drawings:—

Figure 1 is a perspective view illustrating one embodiment of my invention.

Fig. 2 is a longitudinal sectional view through the barrel, one side being omitted.

Fig. 3 is a cross-section through the barrel; and

Fig. 4 is a front elevation, illustrating a slightly modified form of the invention.

In the embodiment of my invention here shown, I have provided a plurality of superimposed hoops 1 to 6, the intermediate hoops being of greater diameter than the end hoops, whereby the bilge of the barrel is formed. Each of the hoops is of a stiff, rigid, or solid construction, so that flexible staves may be woven in and out among the hoops without bending or distorting the same.

Referring to Fig. 1, 7 and 8 indicate two such flexible strips or staves. These strips may consist of wood veneer, or other thin flexible material. It should be noticed that the strip 7 is directed over the hoop 1, as indicated at 9, while the strip 8 is directed under the hoop 1, as indicated at 10. The strip 7 is directed under the hoop 2, over the hoop 3, under the hoop 4, etc., while the strip 8 is directed above the hoop 2, and under the hoop 3, and so on. The manner of interweaving the strips among the hoops will be obvious from an inspection of the drawing.

It will be seen that by this construction, the hoops are securely interlocked with the staves or flexible strips and cannot move in

any direction. The staves are stiffened by the hoops and the latter are in turn reinforced by the staves. One advantage of the above described construction resides in the fact that numerous ventilating passages are thereby formed. In the construction shown in Fig. 1, the strips have parallel edges. This form of strip insures relatively large ventilating openings.

In Fig. 4, however, the strips are tapering, that is, they are widest in the middle, as is clearly shown in the drawing. This arrangement causes the ventilating openings 11¹ to be smaller than the similar openings 70 of the construction shown in Fig. 1.

The ends of the barrel or the ends of the strips are secured by means of reinforcing members or hoops 12 and 13.

The various hoops and flexible strips or staves are held in place without nailing, except where the end hoops 12 and 13 are attached. Should any of the flexible staves become broken, they can be very easily patched and bound together, without weakening or detracting from the appearance of the barrel. The staves used in my construction are much thinner than those employed in standard barrels, whereby a great saving in material is effected.

While I have shown and described one embodiment of my invention and a modified form thereof, it is to be understood that I do not desire to be limited to the constructions herein shown and described, for obvious modifications will be apparent to anyone skilled in the art.

What is claimed is:—

1. In a barrel, a plurality of spaced apart stiff hoops arranged from end to end of the barrel, flexible strips or staves interwoven alternately in and out of said hoops throughout the length of the barrel, and means for connecting the ends of the staves together at the ends of the barrel.

2. In a barrel, a plurality of spaced apart transverse stiff hoops, and longitudinally disposed flexible staves interwoven therewith, said hoops and staves having interlocking engagement with each other, whereby nails are rendered unnecessary for holding said parts in crossed relation, and means for connecting the ends of the staves together at the ends of the barrel.

3. In a barrel, a plurality of spaced apart rigid transverse wooden hoops, strips or staves formed of flexible veneer interwoven

in and out of said hoops throughout the length of the barrel, and reinforcing hoops secured to the staves at the ends of the barrel, said hoops and staves constituting the sole supporting means of said barrel between the ends thereof.

4. In a barrel, a plurality of spaced apart stiff wooden hoops of various diameters arranged in superimposed relation, flexible strips or staves formed of veneer interwoven in and out among said hoops throughout the length of the barrel, the adjacent staves being passed over and under the hoops in

reverse relation, whereby an interlocking engagement of the hoops and staves is made, and the use of nails is obviated, and reinforcing hoops at the ends of the barrel attached to the ends of the strips or staves.

In testimony that I claim the foregoing as my own I have hereto affixed my signature in the presence of two witnesses.

GEORGE FENWICK WARREN.
